UNITED STATES PATENT OFFICE.

CARL GABRIELSON, OF SYRACUSE, NEW YORK, ASSIGNOR TO L. C. SMITH & BROS. TYPE-WRITER COMPANY, OF SYRACUSE, NEW YORK, A CORPORATION OF NEW YORK.

CARD-WRITING PLATEN FOR TYPE-WRITING MACHINES.

1,160,504.

Specification of Letters Patent.

Patented Nov. 16, 1915.

Application filed February 11, 1914. Serial No. 818,135.

To all whom it may concern:

Be it known that I, CARL GABRIELSON, a citizen of the United States, and resident of Syracuse, county of Onondaga, State of New York, have invented certain new and useful Improvements in Card-Writing Platens for Type-Writing Machines, of which the following is a specification.

This invention relates to card writing attachments for typewriting machines and particularly an attachment for writing stencil cards such as used in addressing machines. In writing such cards the ordinary inking ribbon is rendered inoperative to cover the printing point either by removing the ribbon from its guide or, as described in my Patent No. 958,388 dated May 17, 1910, by rendering the ribbon carrier or vibrator inoperative to carry the ribbon to the printing point. The type are thus made to strike the stencil material directly and, as ordinarily used, no ink impression would be made. It is desirable, however, in making some classes of stencil cards to ink the impressions so that they can be easily read, and corrected if necessary and to effect the inking of the impressions without interfering with the crushing effect of the type upon the stencil material, I feed the ink ribbon over the platen and between the card and the platen at the printing point. The impressions on the stencil material are thus inked on the back of the card and the writing is made legible.

My invention will be more fully understood by reference to the accompanying drawings, in which,

Figure 1 is a front view of a typewriter platen equipped with my invention; Fig. 2 is a sectional view on the line 2—2 of Fig. 1; Fig. 3 is a detail view of the platen partly in section; Fig. 4 is an end view of the platen; Fig. 5 is a sectional view on the line 5—5 of Fig. 3; Fig. 6 is a similar view with the platen feed pawl removed; Fig. 7 is a rear view of the card holder; Fig. 8 is an end view thereof; Fig. 9 illustrates means for limiting the rotation of the platen shaft.

Referring to the drawings, 10 indicates a platen shaft which is adapted to rest and turn in the carriage bearings of a visible writing machine and 11 indicates a portion of the carriage frame. Arranged on the shaft and free to turn independently thereof is a cylindrical platen 12. Rigidly secured

to the end of the platen, as shown in Figs. 3, 5 and 6 is a ratchet wheel 13. The platen is held against longitudinal movement on the shaft by disks or collars 14, 15, which are suitably secured to the shaft and turn with it. To the collar 15 a pawl 16 is pivotally connected at 17. As shown this is a gravity pawl projecting from the inner surface of a ring, the weight of the ring tending to hold the pawl in engagement with the teeth of the ratchet wheel and the ring serving to close the space between the disk 15 and the platen and keep the ratchet and pawl free from dust and dirt. It will be seen that when the platen shaft is turned in the direction for spacing between lines of writing the pawl 16 will engage and turn the platen, whereas when the platen shaft is turned backward the pawl will move freely over the teeth of the ratchet wheel 13 without rotating the platen backward. The platen will be held from backward movement by the usual paper feed rolls, to be referred to hereafter.

The disks 14, 15, carry arms 18 which have slots or openings 19 at their outer ends. In front of the platen is a U-shaped card-holder comprising end pieces 20 and a cross piece 21 connecting the bottom ends of the pieces 20. The card holder is provided with pintles 22 which enter the slots in the arms 18 whereby the card holder may be fed up or down as the platen shaft is turned forward or backward. The card holder is also provided at its ends with lugs 23 which slide in fixed guides 24 carried by a stationary bar 25, or other suitable support which is a stationary part of the machine frame. Upon the front of the card holder are suitable spring clips 26 for yieldingly holding the ends of a card and at the bottom of the holder is a ledge 27 for sustaining the card in the holder. The platen may be turned to space between lines by the usual ratchet wheel 28 and its coöperating pawls.

Coöperating with the platen are one or more paper feed rolls 29. These feed rolls may be constructed and operated, for instance, as described in my Patent No. 829,465. Their usual function is to press the paper upon which writing is to be done against the platen so that the paper will feed past the printing point when the platen is turned. In the present instance, a broad ribbon 30 is passed around the platen and feeds with the forward movements of the

platen just as the paper does in ordinary writing. As shown in the drawing the ribbon is carried by a spool 31 and passes around under the platen from the rear to the front thereof and back up over the spool whence it may fall down in the rear of the machine or be wound upon another spool or otherwise temporarily disposed of. After passing through the machine the ribbon may be rewound upon the spool 31 and used again and again until the ink impressions from it become faint.

The operation of the card writing attachment above described is as follows: The platen shaft is turned backward until the card holder is in position for writing the upper line of an address or other matter to be written upon a stencil card and to regulate the position of the upper line and the limits of movement of the card holder up and down stops 32 may be provided to cooperate with the holding pawl 33 of the ratchet wheel 28, as shown in Fig. 9. After writing the upper line the platen shaft is rotated in a direction to raise the card holder into position for writing the second line. The gravity pawl 16 engages the ratchet 13 and turns the platen with the shaft, bringing a new ribbon surface to the printing point and supplying fresh ribbon for inking the second line of characters. In like manner a third line may be written and a fresh inking surface provided therefor. When the card is completed it is taken from the holder and replaced by a new card and the holder is then dropped to position for writing the top line on the card by rotating the platen shaft backward, which may be done by means of the knob 34. During this backward movement of the platen the gravity pawl 16 slips over the teeth of the ratchet wheel 13 and the platen remains stationary, being held from free movement by the feed rolls 29.

Having described my invention what I claim and desire to secure by Letters-Patent is,

1. In a typewriting machine, the combination with a platen and a card holder, adjacent the platen, of a ribbon between the card holder and platen for inking the type impressions on the rear of the card, means for giving the card holder a line space movement, and means for moving the ribbon to present new surfaces at the printing point.
2. In a typewriting machine, the combination with a platen, of a card holder ar-

ranged tangentially to the platen at the printing point, means for feeding the card holder to space between lines on the card, and means coöperating with the platen for feeding a ribbon around the platen and in rear of the card holder, for the purpose set forth.

3. In a typewriting machine, the combination with a platen shaft, of a cylindrical platen mounted on said shaft and free to rotate thereon, a ratchet and pawl device for rotating the platen during forward movements only of the platen shaft, a card holder adjacent the platen, and means on the platen shaft for sustaining the card holder, said card holder being movable up and down as the shaft is moved backward and forward, respectively.

4. In a typewriting machine, the combination with a rotatable platen, of a card holder arranged tangentially to the platen at the printing point thereof, means for moving the card holder up and down to carry successive cards to the printing point, means for advancing the platen in one direction only, and means for feeding a ribbon over the surface of the platen at the printing point and in rear of the card holder, for the purpose set forth.

5. In a typewriting machine, the combination with a platen carriage and platen mounted therein, of a card holding device for sustaining the card over the printing point on the platen, means for imparting a line space movement to the card holder, a ribbon spool supported on the carriage, and means for feeding a ribbon from said spool around the platen and between the card holder and platen, for the purpose set forth.

6. In a typewriting machine, the combination with a carriage having a platen shaft mounted therein, of a platen on said shaft and rotatable relatively thereto, arms fixed on said shaft, a card holder carried by said arms adjacent the printing point on the platen, and ratchet and pawl mechanism between the shaft and the platen whereby the platen is turned in one direction only as the platen shaft is rocked to raise and lower the card holder.

In testimony whereof I affix my signature in presence of two witnesses.

CARL GABRIELSON.
